United States Patent Office.

BENNING ROWELL, OF BYERSVILLE, NEW YORK.

Letters Patent No. 104,065, dated June 7, 1870.

IMPROVEMENT IN FENCES.

The Schedule referred to in these Letters Patent and making part of the same.

To all whom it may concern:

Be it known that I, BENNING ROWELL, of Byersville, in the county of Livingston and State of New York, have invented a new and useful Improvement in Fences; and I do hereby declare that the following is a full, clear, and exact description of the construction and operation of the same, reference being had to the accompanying drawing making a part of this specification, in which—

Figure 1 is a front elevation, and

Figure 2, a side elevation.

This invention consists of panels, each composed of two parallel rails, bearing a lattice-work of slats; said panels being sustained at their ends by trusses, having upper and lower cross-bars, for the support of the parallel rails, and said panels being connected at their ends by perpendicular rods passing through said rails and between the cross-bars of the trusses.

In the drawing—

a a are the parallel rails, and *b* the slats affixed by nails to the rails in the form of lattice-work.

The sustaining trusses *A* are each formed of two side pieces *c c*, inclined toward each other at their tops, the latter being far enough apart to admit the upper rails between them, which rails, both upper and lower, rest on upper and lower pairs of cross-bars *c' c''*, affixed to each side of the posts *e*.

Each pair of cross-bars supports the ends of two rails, and perpendicular rods, *d*, passing between each pair of cross-bars, connect the ends of the panels, each rod *d* passing through four rails.

The lower cross-bars *c''* are mortised out on their upper edges to receive the lower rails.

Those of the slats *b*, next the trusses at each end of each panel, are perpendicular, and the others are inclined and crossed, as shown.

This fence is easily put up, easily taken down, and easily transported.

I am aware that every feature of my invention separately considered is not new, and I therefore do not wish to be understood as claiming any of them alone; but having fully described my invention,

What I do claim as new, and desire to secure by Letters Patent, is—

The combination of the rails *a*, slats *b*, side pieces *c*, cross-bars *c' c''*, and connecting-rods *d*, all constructed and arranged in the manner and for the purpose set forth.

BENNING ROWELL.
